AIR CIRCULATING MEANS FOR DISPLAY FIXTURES

Erhard Allen, Dayton, Ohio, assignor to The Dayton Display Fixture Company, Dayton, Ohio, a corporation of Ohio

Application March 6, 1935, Serial No. 9,619

1 Claim. (Cl. 211—127)

This invention relates to new and useful improvements in air circulating means for display fixtures.

It is the principal object of this invention to provide air circulation means for display fixtures, and particularly those fixtures which support and moisten perishable vegetables and fruits.

Moisture is just as necessary for vegetables as refrigeration is for meats. But moisture alone will not long preserve vegetables and fruit in a fresh condition. A thorough aeration of them from all parts of the supporting fixture is required to keep them from one day to another in a fresh, crisp and colorful state.

The foregoing result is accomplished under my invention by providing horizontal air openings of substantially uniform height in all sides, ends and partitions of the fixture. This air, absorbing external moisture and that produced by the misters, flows freely below, between and over the vegetables and fruit on the reticulated or screen trays to completely aerate them at all times.

Other important and incidental objects will be brought out in the following specification and particularly set forth in the subjoined claim.

In the accompanying drawing, Figure 1 is a perspective view of a vegetable and fruit display fixture provided with my air circulation means. Figure 2 is a cross sectional view of the fixture above its open sides. Figure 3 is a cross sectional view taken through the upper part of the fixture, showing the horizontal openings therein. Figure 4 is a cross sectional view taken through one panel face of the fixture. Figure 5 is a partial plan view of two adjacent reticulated trays, showing one of the water misting tubes. And Figure 6 is a sectional view taken through two adjacent screen trays, showing one of the dividers inverted and one in an upright position.

Referring to the accompanying drawing for a detailed description of my invention, the numeral 1 designates an island fruit and vegetable display fixture of a well-known type, comprising in this instance two end units 2 and 3, and two center units 4 and 5. Each end unit is provided with an outer corner panel 6 and a large side panel 7. Base members 8 surround the end units 3 and 4, the space just above these end members between the corner panels 6, 6 being open to receive heavy metal, perforated boxes 9 which rest on the base.

Projecting between the corner panel members 6, 6 well above the boxes 9, in each end unit

of the fixture is a horizontal channel member 10. Between the top portions of these corner panel members 6, 6 in each end unit, there projects an apron member 11 having a lower horizontal flange between which and the horizontal flange on the channel member 10 there is an opening 12 through which external air may enter the fixture below the vegetables and fruit supported upon reticulated or screen trays 13. A similar horizontal air circulation opening 12 is formed between a top horizontal flange on each corner panel 6 and side panel 7, and a horizontal flange at the bottom of the apron members 14. The latter and the apron members 11 are of approximately uniform width to bring the openings 12 which they form with the members below them, in substantial horizontal alinement. (See Figure 1).

Each of the central units 4 and 5 is provided with a base member 8 between which and a channel member 10 well above it, the unit is open to receive the perforated boxes 9. (See Figures 1 and 2). As shown in Figure 4 the flanged panels and aprons are secured by bolts 15 to vertical angle members 16. Secured to the latter are cap members that are formed inwardly and downwardly to provide flange seats 17 for the screen trays 13.

Secured to the vertical angle members 16 just below the apron 14 of each central unit is a member 18, U-shaped in cross section. A similar U-member 18 is secured to vertical angle members 19 at the middle of the fixture. The horizontal flange on the apron 14 at the front of each central unit is spaced a sufficient distance from the upper horizontal flange to provide another horizontal air circulation opening 12 in substantial alinement with the air openings 12 in the side panels 7, 7 of the end units 3 and 4 respectively. Supported by the lower horizontal flanges of the U-members 18, 18 of each central unit is a water pan 20. (See Figures 2 and 3.)

The upper ends of the front vertical angle members are turned inwardly and downwardly to form flanged seats 21 for the front portions of inclined reticulated or screen trays 22. The rear ends of these trays rest upon flanges 23 formed at the bottoms of elongated U-shaped members 24 that are fitted over the tops of the middle angle members 19.

Secured to these middle angle members 19 are wide apron members 25, 25 formed at their lower ends with horizontal flanges 26, 26 which are spaced a sufficient distance above the top flanges of the rear U-members 18 to provide horizontal

air circulation openings 27 at the rear portions of the central units 4 and 5. These apron members 25, as well as the U-members 18, extend around the ends of the central units 4 and 5 to provide between them continuations of the air circulation openings 27 that register with similar openings in the adjoining ends of the end units 2 and 3, thus providing for a free circulation of air through the sides and ends of all the units 10 comprising the fixture.

As shown in Figure 6 I have provided angle dividing members 28 which may be placed at the middle of the trays in the positions illustrated in that figure, or set upright at other positions to 15 vary the vegetable or fruit-receiving spaces on these trays.

Projecting upwardly through the center units 4 and 5 are water tubes 29, four in this instance, which carry at their upper ends misters 30. 20 Although these misters may be of any suitable type, they are shown as yoke-shaped in Figures 1 and 2. The mist spread by these devices over the vegetables and fruit from above, is assisted in preserving them by the air that enters the fixture 25 through the horizontal openings 12 and 27 from

all sides and ends of the fixture units. This air, which absorbs much external moisture, does not enter the fixture at any one place, but flows into it, and upwardly through the reticulated trays carrying the vegetables and fruit, from all surrounding points. 5

As will be observed from Figure 5, the trays 22 of the central units 3 and 4, are notched at the points where the misting tubes 29 pass them in order that they may fit more closely together. 10

Having described my invention, I claim:

A display stand comprising a frame having sides and ends, reticulated trays mounted in said frame for displaying vegetables and fruits, aprons formed with lower horizontal flanges mounted end 15 to end about the upper sides and ends of the frame, and members having top horizontal flanges mounted in parallelism with the aprons on the sides and ends of the frame, said flanges being spaced a sufficient distance apart to provide horizontal openings through which atmospheric air may be admitted to the frame below said trays from all directions to preserve the perishable articles thereon in a fresh condition. 20

ERHARD ALLEN. 25
